UNITED STATES PATENT OFFICE.

ANTON ROSE, OF CLEVELAND, OHIO.

MECHANISM FOR MAKING LATERALLY-SLOTTED METAL STAMPINGS.

Application filed February 9, 1921. Serial No. 443,687.

To all whom it may concern:

Be it known that I, ANTON ROSE (changed by court order from Anton Ruzicka), a citizen of the United States, and a resident 5 of Cleveland, county of Cuyahoga, and State of Ohio, have invented a new and useful Improvement in Mechanism for Making Laterally-Slotted Metal Stampings, of which the following is a specification, the principle 10 of the invention being herein explained, and the best mode in which I have contemplated applying that principle so as to distinguish it from other inventions.

The present improvements, relating, as indicated, to the making of metal stampings, have more particular regard to the manufacture of so-called snap fasteners or press studs, which consist of a stud member and a socket member, the latter having its characteristic socket formed by the interior of a dome-like projection laterally slotted to receive the ends of a suitably bent spring attached to said member. The stud member is undercut so that when it is inserted in the socket member such spring ends, projecting through the slots in the dome on the latter, will engage such head and hold the parts together. In making the aforesaid socket members the domes are stamped 20 up by a succession of punching operations, and the slots heretofore have been formed therein by bringing the completed domes between pairs of rapidly revolving saws or similarly between movable knives or cutters 25 either oscillatorily or reciprocably mounted. The use of saws in this connection has the objection that the tendency is to leave the edges of the slots ragged, and the knives, where used, have a similar tendency, and 30 either oscillatorily or reciprocably mounted. The use of saws in this connection has the objection that the tendency is to leave the edges of the slots ragged, and the knives, where used, have a similar tendency, and 35 in either case the die mechanism is considerably complicated by adding to the necessary punches for stamping up the dome as aforesaid, either such saws or knives, and providing for their operation in proper 40 fashion.

The object of the present invention, accordingly, is to provide a method and suitably designed punches for use in connection therewith, whereby such lateral slots may 45 be formed in the domes of fastener members of the character described or in any similar connection by means of punches only, no 50 saws, knives or the like being required.

To the accomplishment of the foregoing 55 and related ends, the invention, then, consists of the steps and means hereinafter

fully described and particularly pointed out in the claims, the annexed drawing and the following description setting forth in detail certain means and one mode of carrying out the invention, such disclosed means and mode illustrating, however, but one of various ways in which the principle of the invention may be used.

In said annexed drawing:—

Fig. 1 is a longitudinal central vertical section through a pair of dies equipped with punches of my present improved design, said mechanism being shown in open position, i. e., with punches separated; Fig. 2 is a plan view of the upper or male punch members of the die; Fig. 3 is a similar plan view of the lower or female punch members; Fig. 4 is a central section in the same plane as that of Fig. 1, showing the progressive shaping of a sheet or strip of metal by the successive pairs of punches; Fig. 5 is a sectional view taken at right angles to that of Fig. 1, and on a somewhat larger scale, through one such pair of punches, and shows in similar section the shape of the strip as formed thereby; Figs. 6 and 7 are sectional views similar to that of Fig. 5, but taken through successive pairs of punches of the series; Fig. 8 is a horizontal section taken through the slotted dome on the strip of metal as left by the operation of the pair of punches shown in Fig. 7; Fig. 9 is a perspective view of the co-operative faces of the pair of punches shown in section in Fig. 6; Fig. 10 is a similar perspective view of the co-operative faces of the pair of punches shown in section in Fig. 7; and Fig. 11 is a view illustrating the shearing function of the dies.

Since the manner in which die mechanism is mounted in a press is well understood, it has not been considered necessary to illustrate any part of the press in the drawing, but to confine such illustration to the die mechanism proper, which comprises, as usual, a bed plate 1 that rests on the base of such press, and an upper plate 2 that is suitably secured to the reciprocating head of the press. The male punches are in turn secured to the underside of said upper plate 2, while the corresponding female punches are mounted in a block 3 secured to the upper face of bed plate 1. A stripping plate 4, formed with a series of apertures 6, through which the upper punches are adapted to pass, serves the usual function of freeing the

strip or sheet of metal being operated upon from such punches when they are retracted. Such strip, it will be understood, passes through the die mechanism between such 5 stripping plate and the block 3 in which the lower or female punch members are mounted.

In the illustrative form of the mechanism shown in the drawing a series of seven 10 punches is provided, these being adapted to act simultaneously on a strip of metal, whereby, as such strip A is advanced step by step, a series of dome-like projections a' , a^2 , a^3 , a^4 , a^5 , a^6 and a^7 is formed as shown 15 in Fig. 4. The character of these projections and the manner in which they are formed by the several pairs of punches will now be more specifically set forth.

The first pair of punches 10 and 10^a serve 20 to punch up the shallow rounded dome-like projection a' , following which the punches 11 and 11^a draw such projection into the slightly more elongated form a^2 having its diameter somewhat reduced. It will be 25 noted that the female punch member 11^a is resiliently supported by means of a spring 11^b in the block 3, so as to cause said punch to normally project a short distance above the upper face of the block.

30 The male punch 12 of the next pair has its extremity reduced so as to leave a shoulder, as clearly shown in Fig. 1, and the corresponding female punch comprises a bushing 12^a within which is resiliently supported, 35 by means of a spring 12^b, a central plunger 12^c that conforms with the end of said punch 12, while the opening in the bushing is of a diameter corresponding with the base or shouldered portion of said punch 12. The 40 result of the coaction of these two punches, accordingly, is to shape or draw the dome-like projection on the strip A into the shouldered form a^3 (Fig. 4).

The male punch 13 of the fourth pair is 45 terminally formed similar to the end of punch 12, but instead of having a completely encircling shoulder, it is provided with a pair of oppositely disposed shoulders 13^a. The complementary female punch comprises 50 a bushing 13^b that is formed with raised lands 13^c disposed to lie at right angles to shoulders 13^a on punch 13, while a plunger 13^d is resiliently supported centrally in said bushing by means of a spring 13^e. The 55 result of the coaction of these two punch members is to draw the metal in the encircling shoulder of projection a^3 into opposed sloping shoulders characterizing the form a^4 of the projection as shown in Fig. 4 (see also Fig. 6). The ends of punch 13 and of plunger 13^d leave the body of the projection practically unchanged from the previous form a^3 .

60 The next, i. e. fifth, pair of punches, includes a male punch 14 shown in enlarged

detail in Figs. 7 and 10, from which it will be seen that the end portion 14^a of said punch resembles the frustum of a cone with its base directed outwardly, such end portion being surrounded by a cup-shaped base portion 14^b, the edge of which is sharpened. Both such end and base portions are cut away on opposite sides at 14^c, and the lateral edges at 14^d of the base portion are likewise sharpened, so that the two sections of the base portion which correspond in location with that of the two shoulders on the stamped up projection a^4 , as left by the fourth operation, are adapted to shear such shoulders from the adjacent walls of the dome proper along both their transverse and vertical lines of juncture therewith. The co-operative female punch comprises a bushing 14^e, centrally mounted in which is a plunger 14^f normally held in raised position by a spring 14^g. The upper portion 14ⁱ of the bore in which the plunger is thus reciprocably held is circularly undercut as best shown in Fig. 7, and oppositely extending radial recesses 14^h, as best shown in Figs. 1 and 10, are formed in the face of said bushing to a depth equal to that of such undercut portion of the bore. The portions of the edge surrounding such bore lying between recesses 14^h are so located as to co-operate with the sharpened edges of shoulders 14^b on the male punch, when the two punches are brought together, thus insuring the cutting of a clean slit when the shoulders on the stamped up projection are severed from the latter. At the same time the shoulders 14ⁱ on the female punch will depress or flatten out the shoulders on the stamping as the two punch parts are brought together, leaving a slot in each side of the now practically finished dome, as shown in Figs. 7 and 8.

65 As can be seen from an inspection of the drawing and more particularly of Fig. 11, the shoulders of the fastener member where attached to the dome are sheared therefrom between the sharpened edges of the member 14^b and of the members 14ⁱ. Further movement of the dies causes the members 14ⁱ to flatten out the sheared shoulders against the under side of the punch or die 14. As a 70 consequence of this operation, the adjacent edges of such shoulders will be forced past the cutting edges of the member 14^b and will be caused to lie slightly under such cutting edges or inside the frustum of such member; but due to the thinness of the metal used in the manufacture of fasteners of the type in hand, said member 14^b is easily withdrawn. During the withdrawal of said member, the previously flattened out shoulders 75 spring back slightly and then return to their flattened condition after the punch 14 is completely removed from contact therewith.

80 The two remaining pairs of punches 15, 15^a and 16, 16^a, are of familiar construc-

tion in die mechanism of the class in hand, designed for stamping up snap fastener parts. In other words, punch 15 is provided with a plurality of circularly spaced 5 projections 15^b that are adapted to enter corresponding recesses 15^c in the lower punch 15^a, whereby appropriate holes are formed in the flat portion of the strip around the previously slotted boss or dome 10 for the purpose of sewing the fastener part when finished to a garment or the like. Of the final pair, lower punch 16^a consists, as shown, of a bushing with a central plunger 16^b resiliently supported by a spring 16^c, 15 and said punch co-operates with the upper punch 16 to size and to finish the previously stamped up and slotted fastener part. If necessary, the die members illustrated at 16 can be used to finally flatten out the 20 shoulders.

The manner in which the fastener parts as thus finished are separated from the strip or sheet forms no part of the present invention. In other words, the product of the 25 die mechanism as just described consists of a strip or sheet with a succession of stamped up laterally slotted bosses or domes formed therein of the kind shown at a', Fig. 4. It will be understood that a number of sets 30 of punches such as just described may be arranged side by side, and be caused to operate simultaneously on a wider strip of material to form such bosses or domes in plural series; also that suitable means will 35 be provided to feed the strip through between the mechanism so as to advance the same step by step through a distance equal to that between any two successive punches, all of which are of course spaced equal 40 distances apart. While in the mechanism as illustrated and described the forming shoulders 13^a on upper punch 13, and the cutting shoulders 14^b on upper punch 14, together with the co-operative parts of the corresponding lower punches, are disposed so as 45 to form the slots in the domes or bosses on opposite sides of the axis of the strip or a line passing through the series of such domes or bosses, it will be evident that by 50 placing the punches in question in a different angular position about their respective axes, the location of the slots relatively to such line can be changed as desired. There is no limitation, in other words, in this 55 respect, such as is incurred where saws or knives are employed as heretofore to form the slots in question, and where plural rows of domes are being simultaneously formed

it is not necessary that the angular location of the slots be the same in each such series. 60

The die mechanism is much simplified in any event by the elimination of such saws or knives, and the necessarily more or less complicated devices required to actuate the same in proper timed relation with the 65 movement of the die parts. By forming the slots in the fashion hereinbefore described, the operation becomes a simple punching operation, with no possibility of lost motion, and the cutting of the slots furthermore does not involve the bodily removal of any of the material of the strip, and thus produces no small pieces of metal to clog and interfere with the cutting of the slots. 70

Other modes of applying the principle of 75 my invention may be employed instead of the one explained, change being made as regards the means herein disclosed, provided those stated by any of the following claims or their equivalents be employed. 80

I therefore particularly point out and distinctly claim as my invention:—

1. In mechanism of the character described, the combination with a series of paired male and female dies adapted to form 85 in a sheet a dome-like projection having sloping shoulders on opposite sides, of a pair of dies formed with co-operating cutting edges adapted to shear such shoulders adjacent the dome proper. 90

2. In mechanism of the character described, the combination with a series of paired male and female dies adapted to form in a sheet a dome-like projection having sloping shoulders on opposite sides, of a pair of dies formed with co-operating cutting edges adapted to shear such shoulders adjacent the dome proper, and with opposed flat faces adapted to flatten out such shoulders to the plane of the sheet after being 100 thus sheared. 95

3. In mechanism of the character described, the combination with a series of paired male and female dies adapted to form 105 in a sheet a dome-like projection having sloping shoulders on opposite sides, of a pair of dies formed with co-operating transverse and vertical cutting edges adapted to shear such shoulders along both their transverse and vertical lines of juncture with the dome proper, and with opposed flat faces adapted to flatten out such shoulders to the plane of the sheet after being thus sheared. 110

Signed by me, this 7th day of February, 1921.

ANTON ROSE.
